UNITED STATES PATENT OFFICE.

FREDERICK ABERLE, OF BRIDGEPORT, CONNECTICUT.

STEAM-ENGINE INDICATOR.

SPECIFICATION forming part of Letters Patent No. 740,211, dated September 29, 1903.

Application filed April 5, 1902. Serial No. 101,602. (No model.)

To all whom it may concern:

Be it known that I, FREDERICK ABERLE, a citizen of the United States, and a resident of Bridgeport, in the county of Fairfield and State of Connecticut, have invented certain new and useful Improvements in Steam-Engine Indicators, of which the following is a specification.

My invention relates to an improvement in steam-engine indicators; and it consists in certain details of construction whereby the spool or drum carriage can be operated independently of the paper-carrying drum or both drum-carriage and drum operated together.

To enable others to understand my invention, reference is had to the accompanying drawings, in which—

Figure 1 represents a side elevation of the drum and drum-carriage and broken view of the driving-cord. Fig. 2 is a central sectional view of the drum-carriage and elevating-nut. Fig. 3 is a central sectional view of the drum, showing the same elevated out of driving engagement with the drum-carriage. Fig. 4 is a detail upper plan view of the support for the drum. Fig. 5 is a broken sectional view of the lower part of the drum, full view of the drum-carriage, showing a modified construction for driving the drum. Fig. 6 is an upper plan view of the upper surface of the drum-carriage shown at Fig. 5. Fig. 7 is a broken sectional view of the lower part of the drum, full view of the drum-carriage, being a modified construction for supporting the drum directly on the upper surface of said carriage. Fig. 8 is a detail plan view of the plate connected with the drum-lifting mechanism.

Its construction and operation are as follows:

1 is the drum; 2, the drum-carriage; 2^a, upper surface of the same; 3, the driving-cord connected with said carriage in the usual manner. Heretofore the drum-carriage was provided with a vertical circular flange extending a short distance above its upper surface, to which flange the lower open mouth of the drum was firmly attached by frictional contact, so that both drum and carriage would rotate in unison. With this construction it was necessary to unhook the driving-cord and

stop both the drum and its carriage in order to remove one paper from the drum and insert another. With my improvement I have so constructed the carriage and drum that the drum can be temporarily suspended from the rotative influence of its carriage while the change above described is taking place.

Referring to Fig. 2, 4 is a circular projection rising from the upper surface 2^a of the carriage and integral therewith. Its upper end is provided (see also Fig. 4) with the circular flanged portion 4^a.

5 is a web secured to the interior of the drum 1, and 6 is a circular hub portion secured to said web. The lower end of this hub is provided with the flanged portion 6^a, corresponding to the flange 4^a of the drum-supporting projection 4 of the carriage.

7 is a driving-pin carried by the upper flange 6^a, which pin is adapted to engage with the hole 8 in the lower flange 4^a, so as to bring the drum under the rotative or oscillating influence of the carriage.

9 is the usual drum-supporting stud, which stud passes freely through the drum and carriage, but is adapted to fit snugly in the spring-case 10. The lower end of said stud carries the usual tightening-nut 11 for securing the entire construction to the frame (not shown) of the indicator.

12 is a combined drum-tightening and drum-lifting nut mounted upon the upper projecting end of the stud 9. The upper end of this nut has the female-threaded portion 12^a, adapted to engage the short male-threaded portion 9^a at the top of the stud 9 for the purpose presently to be described.

13 is a plug screwed into the lower end of the nut 12, having a female thread in its lower end adapted to engage with the short male thread 9^b of the stud 9.

14 (see also Fig. 8) is a thin metal plate having the large central hole 14^a, adapted to loosely embrace the smooth shank portion 13^a of the stud 13. 15 represents holes in said plate to receive the screws 16 for securing it to the top 1^a of the drum. The object of making the nut in two parts is to make a better connection with the plate 14, and therefore the whole construction will simply be designated as a "nut."

Whenever it is found desirable to raise the drum out of the rotative influence of the carriage and bring it to a standstill, the nut 12 is turned until it is disengaged from the 5 threaded portion 9^b of the stud 9, when it is carried over the threadless portion 9^c until its upper threaded portion is brought into engagement with the upper threaded portion 9^a of the said stud. This will have carried the 10 flanges 4^a and 6^a, Fig. 4, far enough apart to have disengaged the driving-pin 7. The drum will now be at a standstill, while the carriage 2 will continue to rotate. Breaking the engagement of the nut with the threaded portion 15 9^a of the stud will cause said nut to fall of its own weight until the lower end of the nut rests on the top of the threaded portion 9^b of the drum-stud. However, before it reaches said threaded portion the end of the 20 driving-pin will have come into engagement with the upper surface of the rotating flange 4^a of the carriage and will instantly drop into the hole 8, Fig. 4, of said flange and be again brought under the rotative influence of said 25 carriage. The nut is then screwed down firmly onto the drum. The purpose of the threadless portion 9^c of the stud 9 is to enable the drum, as before mentioned, to fall by gravity and reengage with the carriage before the threaded portion 9^b is engaged by 30 the nut; otherwise if the thread continued the entire distance and the engagement of the pin 7 was controlled by such thread the nut might be tightened before the pin 7 had 35 dropped into the hole 8, and thus make an imperfect engagement. If desired, the holes in the flange 4^a could be increased to any desired number, so as to insure a quicker engagement of the pin. If found desirable, also, 40 the plate 14 could be made flexible, so as to act as a spring.

In the modification shown at Fig. 5 the driving-pin 7^a is secured to the web 5 and is adapted to enter the hole 8^a, Fig. 6. This arrangement is as efficient as that shown in the other views.

Another modification is shown at Fig. 7, wherein the flange portion 6^a of the hub 6 is supported directly on the upper surface of 50 the drum-carriage, the driving-pin entering a hole (not shown) in such upper surface.

While I show and describe means whereby the drum is brought under the rotative influence of its carriage, and call the same a 55 "driving-pin," I wish it distinctly understood that this term comprises any and all equivalent means whereby the said drum and carriage can be readily connected and disconnected for the purpose described.

60 While I show the web 5 placed within the drum and carrying a flanged hub adapted either to rest on a flanged projection rising from the upper plate of the drum-carriage or resting directly on such upper surface or 65 plate, I wish it distinctly understood that I do not wish to be confined to this exact con-

struction, as the web could be lowered so as to close the mouth of the drum, which would then give the drum a top and bottom head with the lower head resting directly on the 70 upper surface of the carriage or on a slight raised projection on such upper surface; nor do I wish to be strictly confined to the means shown for elevating the drum, but consider myself at liberty to employ any and all equivalent means for lifting and temporarily holding the drum out of engagement with its carriage. The gist of my invention lies in so constructing the drum and its carriage that said drum is allowed a free vertical movement 80 on its stud while the carriage is in motion, combined with suitable means, either on said drum or carriage, for bringing the drum and carriage into operative engagement with each other, said engagement adapted to be readily 85 disconnected or broken, so that the drum may be raised on its stud and temporarily held out of engagement with its carriage, and means for securing the drum to the carriage when the two are brought into engagement 90 with each other.

Having thus described my invention, what I claim as new, and desire to secure by Letters Patent, is—

1. An improvement in steam-engine indicators, comprising, in combination with an oscillating drum-carriage, a paper-carrying drum and a central supporting-stud therefor, of a driver on said carriage adapted to bring said drum under the rotative influence of 95 said carriage, the upper portion of said stud threaded, means provided on the upper end of said drum to engage said threaded portion and elevate said drum out of the rotative influence of said carriage, for the purpose set 100 forth.

2. An improvement in steam-engine indicators, comprising, in combination with an oscillating drum-carriage and a central supporting-stud, of a paper-carrying drum 110 mounted on said stud and adapted to have both a horizontal and a vertical movement thereon, said horizontal movement effected by a driver on said carriage, the upper end of said stud threaded, a nut carried by said 115 drum adapted to engage said thread to raise said drum temporarily out of the rotative influence of said carriage, for the purpose set forth.

3. The herein-described improvement in 120 steam-engine indicators, comprising, in combination with an oscillating drum-carriage and a central drum-supporting stud, a drum adapted to have both a vertical and a horizontal movement on said stud independent 125 of the carriage, a driver to bring said drum under the oscillating influence of said carriage, the upper projecting end of the stud having threaded portions separated from each other, a combined lifting and tightening nut 130 mounted on such projecting end, a plate attached to the upper end of said drum and

loosely connected with said nut so that, by means of said nut, plate and threaded portions of the stud, the drum may be elevated and brought to a standstill or into reciprocal relation with the carriage and temporarily maintained there, for the purpose set forth.

Signed at Bridgeport, in the county of Fairfield and State of Connecticut, this 24th day of March, A. D. 1902.

FREDERICK ABERLE.
